US00D847144S

(12) **United States Design Patent** (10) Patent No.: **US D847,144 S**
Einspahr et al. (45) Date of Patent: **** Apr. 30, 2019**

(54) **DISPLAY SCREEN OR PORTION THEREOF WITH GRAPHICAL USER INTERFACE**

(71) Applicant: **Palantir Technologies Inc.**, Palo Alto, CA (US)

(72) Inventors: **Ashley Einspahr**, Palo Alto, CA (US); **Andrew Elder**, Cherry Hills Village, CO (US)

(73) Assignee: **PALANTIR TECHNOLOGIES INC.**, Palo Alto, CA (US)

(**) Term: **15 Years**

(21) Appl. No.: **29/570,991**

(22) Filed: **Jul. 13, 2016**

(51) LOC (11) Cl. **14-04**

(52) U.S. Cl.

USPC **D14/485**

(58) **Field of Classification Search**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown in dashed broken lines in the figure illustrates a display screen or portion thereof and forms no part of the claimed design. The remaining dashed broken lines in the FIGURE illustrate portions of the graphical user interface that form no part of the claimed design.

1 Claim, 1 Drawing Sheet
